SHOE-SHAPING MACHINE.

1,331,613.

Specification of Letters Patent.

Patented Feb. 24, 1920.

Application filed August 24, 1916. Serial No. 116,676.

To all whom it may concern:

Be it known that we, CHARLES M. BRADFORD and RALPH C. SIMMONS, citizens of the United States, residing at Boston, in the county of Suffolk and State of Massachusetts, and Beverly, in the county of Essex and State of Massachusetts, respectively, have invented certain Improvements in Shoe-Shaping Machines, of which the following 10 description, in connection with the accompanying drawings, is a specification, like reference characters on the drawings indicating like parts in the several figures.

This invention relates to machines for 15 shaping shoes and is of particular utility as applied to the operation of shaping turn shoes in conformity to their lasts after the turning and relasting operations have been performed. It will be evident, however, 20 from a consideration of the construction and mode of operation of the illustrative machine that the invention is not restricted in its application to the treatment of shoes of any particular type.

25 After a shoe has been turned and a last has been inserted, it is the usual practice to subject portions of the upper on the last to a beating operation in order to eliminate wrinkles and cause the upper to conform 30 closely to the last. It is particularly desirable to treat in this manner the sides of the upper, including the portions in and adjacent to the crease between the upper and the sole, and also the top of the forepart 35 of the upper. A practically unavoidable effect of the beating tool in the crease adjacent to the sole, however, is the opening or widening of the crease through the downward bending of the projecting edge portion 40 of the sole. For this as well as other reasons, therefore, it is desirable, for the best results, to subject the sole as well as the upper to treatment, particularly the marginal portion of the sole, in order to insure 45 a shapely appearance in the finished shoe.

Important objects of this invention are to provide in a single machine improved shoe shaping means in the use of which the shoe may be readily manipulated to secure the 50 precise results required, and to provide improved means for use in shaping both the upper and the sole of the shoe.

To the above and other ends, an important feature of the invention consists in a novel

combination and arrangement of mechanism 55 designed to facilitate the presentation of a shoe to different tools in succession to cause the upper to be shaped in conformity to the last and to cause the sole to be operated upon to insure a close relation between the 60 upper and the projecting edge portion of the sole and a shapely appearance of the sole in the finished shoe.

Other features of the invention reside in 65 novel means for operating upon the upper of a shoe, including tools of a novel shape, and also a novel arrangement of the tool with reference to its operating means to facilitate the effective treatment of the shoe.

We do not, however, claim in this application 70 the sole shaping tool and its operating means *per se*, since that is claimed in the application for Letters Patent for an improvement in shoe shaping machines having Serial No. 264,641 filed by us on November 29, 1918, and being a division of the 75 present application.

The above and other features of the invention, including certain details of construction and combinations of parts, will 80 now be described with reference to the accompanying drawings and pointed out in the claims.

In the drawings:

Figure 1 is a view in front elevation of a 85 machine in which the invention is embodied,

Fig. 2 is a view of the machine in side elevation,

Fig. 3 is a plan view of a portion of the machine with the frame shown in section 90 on the line 3—3 of Fig. 2,

Fig. 4 is a detail, in front elevation, of the means for operating the upper beating tool,

Fig. 5 is a view in vertical section through a grease dispenser with which the machine 95 is provided,

Fig. 6 shows a portion of the grease dispenser valve detached,

Fig. 7 shows an alternative construction of upper beating tool in which a portion is detachable.

Fig. 8 shows an upper beating tool of different construction from that shown in the other figures, and

Fig. 9 is a section on the line 9—9 of 105 Fig. 8.

The operative parts of the machine are mounted upon a frame 2 and include a main

belt-driven shaft 4 for operating a tool 6 to shape the upper of a shoe and a supplemental shaft 8 for operating a tool 10 to shape the sole, the shaft 8 being driven from the shaft 4 by means of pulleys and a connecting belt 12. The tool 10, as will be noted by reference to the front view of the machine, Fig. 1, is offset laterally from the tool 6 but is within convenient reach of the operator as he stands in front of the machine, the arrangement thus permitting the use of either tool at will without the necessity for any material change of position on the part of the operator.

15 The tool 6 is arranged to be operated by means such as that disclosed in United States Patent No. 768,560, granted upon the application of L. A. Casgrain on Aug. 23,

1904, comprising an annular series of rolls 20 14 carried by a drum 16 on the shaft 4 and arranged to impart downward impulses in rapid succession to a bar 18 which is slid- 25 ingly mounted for vertical reciprocatory movement and to the lower end of which

30 the tool 6 is secured. The bar 18 is arranged to be pushed upwardly into the path of the rolls 16 by upward pressure of the work against the tool 6, and is normally main- 35 tained by gravity in its idle position in

which it is supported by the head of a stop screw 20 in engagement with a lug 22 on the side of the bar. Upward pressure of a 40 shoe against the tool 6 thus causes the tool to receive percussional impulses in rapid

45 succession as long as the shoe is pressed against it, the tool having substantially a beating effect upon the shoe, wherefore the tool 6 is termed herein a beating tool.

By reference to Figs. 1 and 2 it will be 40 seen that the tool 6, as herein shown, comprises two portions or members 23 and 25, of which the member 23 is shaped to operate upon the upper at the sides of a shoe and the member 25 to treat the upper at the 45 toe. The side engaging member 23 of the tool is arranged to extend horizontally from side to side at the front of the machine and has opposite end portions substantially identical in shape to permit opposite sides of a shoe to be presented alternately to the tool without the necessity of reversing the shoe end for end. In order that the member 23 may effectively engage different portions of 50 an upper upon a last, its shoe engaging face presents a transverse convex curvature, and for the same purpose, as well as to facilitate engagement in the crease between the upper and the sole, the member 23 is also convexly curved transversely across each end, that is 55 to say, the ends of member 23 are so shaped as to appear convex in a plan view. The member, moreover, tapers toward each end to a comparatively thin edge for engage- 60 ment in the crease. In order that the tool 65 may be used also for shaping the upper

upon the top of the forepart of the shoe, as well as to improve the effectiveness of the tool upon the sides of the shoe, the shoe engaging face of the member 23 presents a concave curvature extending longitudinally 70 of the tool. The intermediate portion is thus adapted to treat the top of the forepart of the upper, while the end portions are adapted for treating the sides. By reference to Fig. 2 it will be seen that the member 23 is inclined downwardly from front to rear at an angle to its path of reciprocatory movement, thus causing its shoe engaging surface to face somewhat toward the front. One purpose and effect of this arrangement is to render the manipulation of the shoe easier for the operator, since the shoe may be more conveniently presented to the tool and more easily held against it with the necessary pressure if somewhat inclined 80 from the front downwardly than if held in a horizontal position while pressed upwardly and moved to bring different portions into engagement with the tool.

The member 25 comprises a projection of 90 the tool 6 somewhat above and at the front of the member 23, and is shaped for engagement with the upper at the toe while the shoe is held with the top of the forepart facing the operator, the position of this 95 member at the front of the tool being such that the shoe may be more conveniently presented for treatment of its toe portion, when required, than if the portion 23 were depended upon to treat the toe as well as the 100 sides of the shoe. In the construction shown in Figs. 1 and 2 the member 25 constitutes an integral part of the tool 6, while in the construction shown in Fig. 7, which may be used as an alternative construction, the 105 member 25 is detachable from other portions of the tool in order to permit it to be replaced or to be removed where its use is not desired.

On most classes of work it is desirable to 110 subject the upper to the influence of heat as well as to percussional impulses in order to facilitate the shaping of the upper to the last through the shrinking action of heat upon the leather. To this end the machine shown 115 includes means for heating the tool 6 comprising a gas flame directed against the tool from a burner 24 which is supplied with gas from a conduit 26, the flame being directed into a hollowed out portion on the rear side 120 of the tool 6, as shown by Fig. 2. The flow of gas and consequently the degree of heat in the tool is regulated by a valve 27. The reciprocatory movements of the tool, it will be understood, are sufficiently short to insure that the flame shall not be projected beyond the edges of the tool into engagement with the work. It will likewise be understood that the disclosure of this particular heating means is merely illustrative and 125 130

that various means may be employed for heating the tool.

In order that the tool 6 may be maintained at such a temperature as to insure effective results without becoming over-heated in such manner as to injure the work, it is desirable that means be provided for indicating continuously the temperature of the tool. To this end the tool is projected somewhat toward the front from the bar 18 and is bored vertically at 28 to receive the bulb of a thermometer 30 which is mounted upon the front of the frame. While the bore 28 is made somewhat larger than the bulb in order to avoid breaking the bulb during the operation of the tool, and consequently the thermometer will not register precisely the degree of heat in the tool, this difference will be recognized as substantially constant, and with proper allowance for the difference the temperature of the tool may be determined with sufficient accuracy for practical purposes.

In connection particularly with the means for heating the tool, a further important advantage attaches to the manner in which the tool is mounted, as hereinbefore described, with its upper engaging surface directed generally in inclined relation to its path of reciprocatory movement. It will be evident that with the surface of the work presented to the tool thus inclined to the direction of the beating impulse of the tool a slight relative slip between the tool and the shoe will take place at each impulse, the tool thus having an ironing effect in addition to its beating effect. Among other advantages this serves as insurance against burning the leather by a dwell of the heated tool too long in contact with the same portion of the surface.

Figs. 8 and 9 show an alternative form of upper beating tool 6' which is secured to a vertically reciprocatory bar 18' similar to the bar 18 of Figs. 2 and 4. The tool 6', when used, should preferably extend in substantially the same relation to the machine as the tool 6 in Figs. 1 and 2, and as shown in Fig. 9 this tool has a lower surface curved transversely for engagement with the shoe, the tool being extended, as shown in Fig. 8, to permit it to be used for shaping portions such as the top of the forepart of the upper and having an end portion tapering toward its outer extremity and presenting a lower surface convexly curved in different directions in order to facilitate engagement of the tool with the upper in the shank and close to the sole. The tool 6', moreover, has at its inner end a portion 31 shaped especially for engagement with the upper in the crease adjacent to the sole. The tool in the construction shown is arranged to be heated by a gas flame issuing from a stationary burner 24', the tool being bored longitudinally

to receive the flame and having openings 33 for the escape of the products of combustion. In order to facilitate the heating of the outer end portion of the tool, the tool is inclined upwardly as shown in Fig. 8.

The sole shaping tool 10 is carried by one arm 32 of a bell crank lever which is mounted on a rock shaft 34, the other arm 36 of the bell crank extending rearwardly toward the end of the shaft 8. The arm 36 is forked at its rear end, and clamped to the forked portion is a rod 38 upon which a block 40 is slidably mounted. The shaft 8 is provided at its front end with a crank disk 42 which carries a crank pin 44, the projecting end of the pin 44 being journaled in the block 40. The pin 44 is mounted on an eccentric 46 which is adjustable in the disk 42 to vary the eccentricity or throw of the crank pin and is secured in adjusted position by means of a bolt 48. Through these connections the bell crank 32, 36 and the tool 10 will be rapidly oscillated in a continuous manner toward and from the operator during the operation of the machine.

It will be observed that the arm 32 is normally inclined forwardly from the vertical and consequently determines a path of movement of the tool 10 which is inclined downwardly from front to rear, this incline being substantially or approximately the same as the inclination of the portion 23 of the tool 6. The purpose and effect of this arrangement is to facilitate the presentation of the shoe to the tool 10 in substantially the same manner as previously explained with reference to the tool 6, it being much easier for the operator to press the shoe diagonally upward and backward than directly upward against the tool. Since the tool 10 extends transversely at the front of the machine, in substantially the same relation to the machine as the member 23, the shoe may be presented to this member and to the tool 10 successively without any substantial change in the lengthwise inclination of the shoe. In the construction shown the tool 10 is shaped to rub the sole, but it should be understood that in its broader aspects the invention is not limited to a rubbing tool. The longitudinal concave curvature of the shoe engaging surface of the tool 10, as well as its transverse convex curvature, as shown, facilitates the engagement of the tool with all portions of the sole which it may be desired to treat and renders the tool particularly effective for shaping the marginal portion of the sole.

In the operation of the machine on some classes of work, such, for example, as shoes made of patent or enameled leather, it is desirable, in order additionally to insure against burning the leather by contact with the heated tool 6, to apply a small quantity

of oil or grease to the surface under treatment. The machine is accordingly provided with grease dispensing means comprising a receptacle 50 mounted upon a bracket 52 on the frame in convenient position for use and having an outlet opening in its bottom portion normally closed by a valve 54 which rests upon a beveled seat on the receptacle and is maintained normally by its own weight in position to close the outlet. The valve has a depending portion 56 which closely fits in the bore of the outlet opening and is arranged to be engaged by the shoe to lift the valve. In the depending stem 56 close to the valve seat is an annular recess 58 and extending downwardly from this recess on opposite sides of the stem are fluid conducting grooves 60 which terminate at the lower end of the stem. When the valve is momentarily lifted, therefore, a small quantity of the fluid will be admitted to the recess 58 whence it will run down the grooves 60 to the lower end of the valve and hang suspended in drops for application to the work when the work is presented in engagement with the end of the stem. It will be evident that the flow of the fluid down the grooves 60 will continue after the valve has closed. In order to localize and hold the drops of fluid for application to the work, the end of the stem 56 is provided with depending projections 62 in line with the grooves 60. The grease in the receptacle 50 is maintained in a fluid condition to cause it to flow readily by means of heat applied to the receptacle by a gas burner 64.

In the operation of the machine the heated tool 6 will first be used, the shoe being pressed upwardly against the tool to cause the tool to receive percussional impulses from its operating means. For the treatment of the side of the shoe close to the sole the shoe will be positioned to cause an end of the portion 23 of the tool to project into the crease between the upper and the sole and will be moved longitudinally to cause the tool to engage different portions of the upper. If application of grease to the work is desirable, this may be effected by engagement of the shoe with the stem 56 of the valve 54. After one side of the shoe has been treated the shoe will usually be turned about its longitudinal axis and the other side presented to the opposite end of the tool, although the shoe may, if preferred, be turned end for end and the other side presented to the same end of the tool. If desired also other portions of the upper, such as the top of the forepart, may be shaped by engagement with the tool 6, preferably on the concave intermediate portion of the member 23; and if the condition of the shoe requires the shaping of portions of the upper about the toe

the shoe may be presented to the member 25 as shown in Fig. 2, although this operation may be postponed until after the shoe has been presented to the sole rubbing tool. While held with its longitudinal axis 70 in the same or approximately the same angular relation to the machine as when the sides and the top of the forepart are presented for treatment the shoe may next be presented with such portions of its sole as may 75 be observed by the operator to require treatment in engagement with the oscillating tool 10, this tool serving to even the surface of the sole and press the edges toward the upper in such manner as to insure a close 80 crease in case the edges may have been bent away from the upper in the preceding upper shaping operation.

In the use of the alternative form of tool shown in Fig. 8 both sides of the shoe are 85 presented to the same end portion of the tool, the shoe being turned end for end, and the member 31 is also used for shaping the upper in the crease at both sides of the shoe as well as around the toe. The top of 90 the forepart of the upper also may be shaped by engagement with the extended intermediate portion of the tool.

It will be evident from a consideration of the foregoing disclosure that this invention 95 provides a machine which is especially useful in the production of a high grade and maximum quantity of work, particularly by reason of its adaptability to the varying shapes of different styles and sizes of shoes, 100 the facility with which the work may be manipulated to cause the tool to engage all portions which require treatment and in presenting the work to different tools in succession, and the ease with which the operation of the machine upon the work may be observed.

It will be apparent also that the rapid reciprocating movement of the tool, as well as the relative slip between the tool and the 110 shoe, will tend to obviate any burning of the leather by its contact with the heated upper engaging tool, since a dwell of the tool upon any portion of the surface for such a length of time as to burn the material 115 is thus avoided.

Having described the invention, what we claim as new and desire to secure by Letters Patent of the United States is:

1. A machine of the class described having, in combination, a tool mounted for reciprocatory beating movement in angular relation to the surface of the upper of a shoe presented for treatment, a second tool mounted for reciprocatory movement along 120 the surface of the sole of the shoe to shape the sole, said tools being arranged in such relation as to permit portions of the upper and the sole to be operated upon in succession without substantial change in the length- 125 130

wise inclination of the shoe, and means for operating the tools.

2. A machine of the class described having, in combination, a tool mounted for reciprocatory beating movement in angular relation to the surface of the upper of a shoe presented for treatment, a second tool mounted for reciprocatory movement along the surface of the sole of the shoe to shape the sole following the operation of said first named tool, both tools being arranged to permit the shoe to be pressed upwardly against them with the portion under treatment in view of the operator, and means for operating said tools.

3. A machine of the class described having, in combination, a shoe beating tool shaped for engagement with the upper of a shoe, means for imparting downwardly directed shoe beating movements to the tool, the tool having its upper engaging portion inclined downwardly from front to rear at an acute angle to its direction of movement, and a second tool mounted for reciprocatory movement in a path downwardly inclined from front to rear to shape the sole of the shoe by movement along the surface of the sole following the operation of said first named tool.

4. A machine of the class described having, in combination, a tool mounted for reciprocatory movement to beat the upper of a shoe and shaped for engagement with the upper in the crease adjacent to the margin of the sole, a second tool shaped and mounted to reciprocate along the bottom of the sole at the margin to press the margin toward the upper following the operation of said first tool, the tools being so constructed and arranged as to operate upon the shoe in succession without substantial change in the lengthwise inclination of the shoe, and means for operating said tools.

5. A machine of the class described having, in combination, an upper beating tool and a sole rubbing tool mounted for reciprocatory movement in transverse paths to permit a shoe to be presented to the tools in succession with its longitudinal axis in substantially the same angular relation to the machine, and means for operating said tools.

6. A machine of the class described having, in combination, a reciprocatory shoe beating tool having a surface presenting a concave curvature longitudinally of the tool and in transverse relation to its direction of movement for engagement with the upper of a shoe, and a second reciprocatory tool concavely curved longitudinally for rubbing engagement with the sole of the shoe, said tools being disposed with their longitudinal dimensions extending laterally with respect to the operator's working position to facilitate the presentation of a shoe to the different tools in succession.

7. In a machine of the class described, a reciprocatory shoe beating tool having an end portion shaped for engagement with a shoe upper in the crease between the upper and the sole and another portion convexly curved for engagement with the top of the forepart of the upper, and means for imparting shoe beating movements to the tool.

8. In a machine of the class described, a reciprocatory shoe beating tool having opposite end portions shaped respectively for treating different portions of the upper of a shoe and an intermediate portion shaped for engagement with the top of the forepart of the upper, and means for imparting shoe beating movements to the tool.

9. In a machine of the class described, a shoe beating tool having opposite end portions shaped respectively for engagement with the upper at opposite sides of a shoe to permit the operator to present the opposite sides of the upper alternately to the tool without reversing the shoe end for end, the tool having also a portion shaped for engagement with the upper at the toe end, and means for operating the tool.

10. In a machine of the class described, a reciprocatory shoe beating tool having opposite end portions for engagement with the upper of a shoe in the crease between the upper and the sole and an intermediate portion shaped for engagement with the top of the forepart of the upper, the tool having also a portion above said intermediate portion shaped for engagement with the upper adjacent to the sole at the toe end of the shoe, and means for operating the tool.

11. In a machine of the class described, a reciprocatory shoe beating tool having a member shaped for engagement with the side of a shoe in the crease between the upper and the sole and also with the top of the forepart of the upper, and means for imparting downwardly directed shoe beating movements to the tool in a substantially vertical path, said member being inclined downwardly from front to rear at an angle to its direction of movement to facilitate the presentation of the shoe to the tool, and the tool having also at the front a portion shaped for engagement with the upper at the toe end of the shoe.

12. A machine of the class described having, in combination, upper beating means comprising a beating tool constructed and arranged to operate upon a shoe presented thereto in an inclined position, and means for shaping the sole of the shoe comprising a second tool mounted for reciprocatory movement in a path substantially parallel to the incline of the shoe as presented to said first-named tool.

13. A machine of the class described having, in combination, upper beating means comprising a tool constructed and arranged

- to engage the upper at the side of a shoe with the shoe presented in a position downwardly inclined lengthwise from the front of the machine toward the rear, and means for shaping the sole of the shoe comprising a second tool mounted for reciprocatory movement in a path inclined similarly to the position of the shoe as presented to said first-named tool.
- 10 14. A machine of the class described having, in combination, upper beating means comprising a tool mounted for reciprocatory beating movement in engagement with the upper at the side of a shoe, and means for shaping the sole of the shoe comprising a second tool mounted for reciprocatory movement lengthwise of the sole in transverse relation to the path of movement of said first-named tool.
- 15 15. A machine of the class described having, in combination, a reciprocatory shoe beating tool having opposite end portions shaped respectively for engagement with the upper at opposite sides of a shoe, and means for shaping the sole of the shoe comprising a second tool mounted for reciprocatory movement lengthwise of the sole and arranged to extend transversely of the shoe in substantially the same angular relation to a vertical plane as said first-named tool.
- 20 16. In a machine of the class described, a reciprocatory shoe beating tool having opposite end portions shaped respectively for engagement with the upper at opposite sides of a shoe to permit the operator to present the opposite sides of the upper alternately to the tool without reversing the shoe end for end, the tool having also an intermediate portion shaped for engagement with the top of the forepart of the upper, and means for imparting downwardly directed beating impulses to the tool.
- 25 17. In a machine of the class described, a reciprocatory shoe beating tool having opposite end portions shaped respectively for engagement with the upper at opposite sides of a shoe in the crease between the upper and the sole, said tool extending substantially horizontally in front of the machine with its opposite end portions directed respectively toward the opposite sides of the machine, and means for imparting shoe beating impulses to the tool.
- 30 18. In a machine of the class described, a reciprocatory shoe beating tool having an end portion shaped for engagement with the upper at the side of a shoe, said tool extending transversely of the machine with said end portion directed toward one side of the machine, and means for imparting downwardly directed shoe beating impulses to the tool.
- 35 19. In a machine of the class described, a reciprocatory shoe beating tool having opposite end portions shaped respectively for engagement with the upper at opposite sides of a shoe and an intermediate portion shaped for engagement with the top of the forepart of the upper, said tool extending substantially horizontally and having its shoe engaging surface directed diagonally downward and toward the operator's position in front of the machine, and means for imparting shoe beating impulses to the tool.
- 40 20. In a machine of the class described, a reciprocatory shoe beating tool convexly curved transversely and also convexly curved across its opposite ends to facilitate engagement of the opposite ends of the tool in the crease between the upper and the sole of a shoe, the shoe engaging surface of the tool presenting also a concave curvature lengthwise of the tool to adapt the intermediate portion of the tool for engagement with the upper over the top of the forepart.
- 45 21. In a machine of the class described, a reciprocatory shoe beating tool having opposite ends shaped to engage in the crease between the upper and the sole of a shoe at the sides of the shoe, the tool having also a portion shaped to engage in the crease at the toe end of the shoe, said toe end engaging portion being so arranged as to permit the shoe to be presented thereto with the top of the forepart facing the operator.
- 50 22. In a machine of the class described, an upper shaping tool having a longitudinal concave curvature and a lateral convex curvature, the opposite ends of said tool being shaped to engage a shoe in the crease between the upper and the sole, and means for imparting shoe beating impulses to said tool in the direction of the shoe.
- 55 23. In a machine of the class described, an upper shaping tool having its opposite end portions shaped to engage the sides of a shoe in the crease between the upper and the sole, and means for imparting to said tool shoe beating impulses in a direction substantially perpendicular to the lengthwise dimension of the tool.
- 60 24. In a machine of the class described, an upper shaping tool, means for imparting shoe beating impulses to said tool, and means for heating the tool, the tool having its upper engaging face generally inclined to the path of its beating movement to cause a relative slip between the tool and the surface of the upper at each beating impulse of the tool.
- 65 25. In a machine of the class described, an upper shaping tool constructed for engagement in the crease between the upper and the sole at the side of a shoe, means for imparting shoe beating impulses to said tool, and means for heating the tool, said tool being constructed to operate upon a shoe presented with its longitudinal axis inclined to the direction of the beating movement of the tool.

tool to cause the impulse of the tool to be directed at an acute angle to the surface of the upper.

26. In a machine of the class described, 5 an upper shaping tool, means for imparting to said tool shoe beating impulses directed downward substantially vertically, and means for heating the tool, said tool having its upper engaging surface facing diagonally forward relatively to its path of movement to cause the beating impulse of the tool to be directed at an acute angle to the surface of a shoe presented for treatment.

27. In a machine of the class described, 10 an upper shaping tool having opposite end portions constructed to engage in the crease between the upper and the sole at the sides of a

shoe and a portion between its ends constructed for engagement with the upper over the top of the forepart, means for imparting 20 shoe beating impulses to the tool, and means for heating the tool, the tool being arranged to operate upon a shoe presented thereto in the hands of the operator with the longitudinal axis of the shoe inclined to the direction 25 of movement of the tool.

In testimony whereof I, the said CHARLES M. BRADFORD, have signed my name to this specification.

CHARLES M. BRADFORD. 30

In testimony whereof I, the said RALPH C. SIMMONS, have signed my name to this specification.

RALPH C. SIMMONS.
